UNITED STATES PATENT OFFICE.

LOUIS W. CHISM, OF SPRINGFIELD, MASSACHUSETTS, ASSIGNOR, BY MESNE ASSIGNMENTS, TO THE STEEL PRODUCTS COMPANY, OF HARTFORD, CONNECTICUT, A CORPORATION OF CONNECTICUT.

STORE-SERVICE APPARATUS.

1,347,498.

Specification of Letters Patent.

Patented July 27, 1920.

Application filed May 4, 1914, Serial No. 836,054. Renewed April 22, 1920. Serial No. 375,898.

To all whom it may concern:

Be it known that I, LOUIS W. CHISM, a citizen of the United States, and a resident of Springfield, county of Hampden, and 5 State of Massachusetts, (whose post-office address is 40 Taylor St., Springfield, Mass.,) have invented an Improvement in Store-Service Apparatus, of which the following 10 description, in connection with the accompanying drawings, is a specification, like characters on the drawings representing like parts.

This invention relates to store service apparatus, and more particularly, though not 15 exclusively, to a receiving and sending station, by means of which the carriers are received from and delivered to the main outgoing and incoming elevated tracks of a cable cash carrier system.

20 My invention will be best understood by reference to the following specification, when taken in connection with the accompanying drawings of one specific embodiment thereof, while its scope will be more 25 particularly pointed out in the appended claims.

In the drawings:

Figure 1 is a side elevation of a portion of one form of store service apparatus having 30 a receiving and sending station embodying my invention;

Fig. 2 is a detail elevation on an enlarged scale, showing a portion of the main and branch incoming tracks, with the cable and 35 wheels adjacent the juncture of said tracks;

Fig. 3 is an elevation of a portion of the parts shown in Fig. 2, viewed from the right;

Fig. 4 is a plan of the apparatus shown 40 in Fig. 1;

Fig. 5 is an elevation of the apparatus viewed from the right-hand side of Figs. 1 and 4;

Fig. 6 is a detail, perspective view showing 45 the portion of the sending and receiving tracks of the station, and illustrating particularly the provision for permitting the removal of the carriers from the receiving tracks and the introduction of the carriers 50 onto the sending track;

Fig. 7 is a detail elevation on an enlarged scale, viewed from the opposite side of the apparatus shown in Fig. 1, and illustrating the carrier with its gripping device in en-

gagement with the cable just prior to its dis- 55 engagement therefrom by the gripper operating cam;

Fig. 8 is a bottom plan of the carrier, and a portion of the track as seen in Fig. 7, except that the carrier is moved along into 60 position with its gripping device engaged by the grip-releasing cam;

Fig. 9 is an end elevation of the parts shown in Fig. 8, but with the gripping device released from the cable; 65

Fig. 10 is a detail view at an enlarged scale, illustrating the action of the cable-gripping lever and its co-operating spring.

Referring to the drawings, and to the specific embodiment of my invention which 70 I have selected for illustrative purposes, I have there shown a store service apparatus having a main outgoing or forwarding track 15 leading from a usual cashier's station (not shown), and an incoming or return track 16 leading to the cashier's station. These tracks may be composed of 75 rails of any suitable cross-sectional shape, as, for example, cylindrical rods, herein two for each track and suitably supported in 80 any usual or desired manner. Associated with these tracks is a suitable driving means, herein an endless motor or carrier-propelling cable 17, which in practice will be suitably tensioned and driven. 85

The tracks 15 and 16 are adapted to sustain and guide suitable carriers 18, having provision for engaging the tracks and herein consisting of pairs of guides 19 and 20 on opposite sides of the carrier, separated 90 by grooves 21 adapted to receive the rails of the track. The carriers are provided with suitable cable-gripping devices, herein comprising a fixed arm 22 and a pivoted arm 23, the latter being pivoted at 24 to 95 the body of the carrier, and preferably provided with a cam 25 engaging a spring 26 serving to maintain the arm in either a closed position as shown in Fig. 8, or an open position as shown in Fig. 1. 100

When the pivoted arm is in its closed position, the spring serves to supply the necessary pressure to urge the arm against the cable 17, and consequently pinches or grips the cable against the fixed arm 22. 105 When the pivoted arm is in its open position, the spring serves to maintain the arm in such position out of engagement with the

cable, as clearly shown in Figs. 1, 3, 9 and 10, until it is closed by an appropriate cam. Herein the arm 23 is provided with a cable-receiving notch or depression 27, as is usual with devices of this character, but the arm 22, instead of being notched or grooved, is provided preferably with a substantially flat cable-engaging face 28, for a purpose which will be hereinafter explained.

10 Herein, the rails of the track 15 are disposed in a horizontal plane, so that the carrier travels flatwise thereon, while the rails of the track 16 are preferably, though not necessarily, disposed in a vertical plane, so 15 that the carrier travels edgewise thereon. It will be understood that in practice, the tracks 15 and 16 may connect one or more drop stations with the cashier's station, but for the purpose of the present invention, it 20 will suffice to show and describe merely one of these drop stations. It will be understood that the tracks 15 and 16 will in practice be located at some distance above the counters of the store, usually a distance of 25 several feet.

I will now describe the means by which the carriers are diverted from the main outgoing track into the drop station, and returned therefrom to the main incoming track.

Herein the drop station comprises a branch outgoing or receiving track 29, extending from a point adjacent the main outgoing track 15 to a point adjacent the 35 counter (not shown). This track may be otherwise appropriately constructed, but herein is provided with a horizontal portion 30, herein located above the track 15, and a vertical portion 31 leading downwardly to 40 the counter.

In connection with the receiving track 29, I may employ suitable means for selectively and automatically diverting from the main outgoing or forwarding track 15 such of the 45 carriers as are intended for this particular drop station. For this purpose, I may employ suitable means to engage carriers of a certain configuration, size or other characteristic. Herein, the carrier-diverting means just referred to comprises switch or diverting tracks 32—32, arranged in pairs, two on each side of the carrier, and separated from each other by a slot 33, which receives the supplemental guides or lugs 34—34 provided 55 on the carrier 18.

These guides, as usual, will be placed at various heights upon the carriers, according to the station for which they are intended, and the diverting switch tracks 32—32 will 60 be correspondingly placed as to height from the outgoing or forwarding track 15. Such of the carriers as are not intended for this particular station will pass from left to right (Figs. 1 and 4) beneath the diverting 65 or switching tracks 32, and will pass along

to the station for which they are intended. Such of the carriers as are intended for this particular station will be diverted from the track 15 by the engagement of the supplemental guides or lugs 34—34 with the switch 70 or diverting tracks 32—32, so that the carrier, while still maintaining its hold upon the cable, will be lifted out of coöperation with the track 15, said track for this purpose being provided with suitable offset portions 35—35 (see Fig. 4) to permit the main or principal guides 20—20 to clear such track.

When the carrier is thus diverted from the main outgoing track, it still maintains its hold upon the cable for a time, thus lifting the cable from its normal position, as shown in Fig. 7, and passes into coöperation with the horizontal portion 30 of the receiving track 29, as clearly shown in Fig. 7, 80 the pairs of guides 19 and 20 receiving the rails of said track, as clearly shown therein.

After the carrier passes into coöperation with the track 29, as just described, it passes out of coöperation with the switch or diverting tracks 32, as will be evident from an inspection of Fig. 7. At this point, the carrier is disengaged from the cable by suitable means, herein a cam 36, which is engaged by the cable gripping arm 23 (see Fig. 8), and 90 is swung rearwardly due to the forward motion of the carrier. The arm is swung from the position shown in full lines in Fig. 8 to the position shown in dotted lines therein, thus releasing its hold upon the cable, which 95 will then snap back into its normal path. Since the arm 22 is provided with the flat cable-engaging face 28, as hereinbefore described, such release of the cable will occur without any interference from said arm. The cam 36 will in practice be supported in 100 any usual or desired manner, as by means of a bracket 37, which herein also serves as one of the supports of the tracks 32, and the horizontal portion 30 of the track 29. In 110 connection with the tracks 32, I may employ, if desired, a suitable guard rail 38, serving to steady the carrier and maintain its proper engagement with said tracks.

When the carrier is released from its 115 driving engagement with the cable, as just described, it travels by its momentum down the receiving track 29, and there may be provided a suitable buffer 39 to receive its impact. The receiving track 29 may have 120 suitable provision for the removal of the carrier therefrom, herein consisting of offset portions 40—40, through which the guides 20 of the carrier may be withdrawn in a wellknown manner, by lifting the carrier 125 and rocking it laterally.

The apparatus as thus far described is merely a typical example of a wellknown store service apparatus, and I wish it to be understood that my present invention is not 130

necessarily limited in its application to this type of apparatus, nor to any of its details. I will now describe one preferred form or embodiment of my present invention, as employed in connection with the apparatus already described.

Leading upwardly from the counter is a sending or branch incoming track 41, having suitable provision for the introduction of the carrier, herein offset portions 42-42, similar to those of the receiving track hereinbefore described. This sending track extends to a point adjacent the main incoming or return track 16, and herein at its juncture therewith enters into the main return track as a branch, the main incoming track being herein provided at the juncture with an interruption or gap 43 in its lower rail, where the branch track rounds into the main track, as clearly shown in Fig. 2. If the apparatus employed were of the type wherein the rails of the main incoming track are disposed in a horizontal plane, it will be obvious that both rails of the track might be provided with an interruption or gap for the entrance of the carrier from the branch incoming track. In either event, it is desirable to provide means for supporting the carrier as it passes the juncture of the branch and main tracks in traveling along the latter, or in other words, a supplemental track or guide to support the carrier as it passes across the gap or interruption in the principal rails of the main incoming track. This supplemental guide or track may take other forms, but herein I employ a supplemental guide 44, which it may be said in a sense bridges the gap or interruptions, in that it extends part way across the gap and supports the carrier as the latter passes across the gap, and until it arrives in a position where it will again engage the lower rail of the main incoming track, or at least until it shall have arrived at a position where its momentum will safely carry it beyond the gap into engagement with the lower rail of the main incoming track. Preferably the upper edge of the supplemental track or guide engages the lower face of the fixed gripper arm 22 of the carrier. This construction possesses the advantage of providing supplemental guiding means requiring no moving parts. This is possible because the supplemental guide, although enabling a carrier upon the main incoming track to clear the gap, safely terminates at such point as to permit a carrier to pass from the branch incoming track onto the main incoming track, without interference from the supplemental guide. This will be clear from an inspection of Fig. 2. The supplemental guide may be otherwise appropriately supported, but herein is secured to a bracket 45. As a means for driving the carriers up-

wardly along the branch incoming or sending track, I have herein provided the driving or propelling cable with a looped portion 46, which may take other forms, but herein appears as a closed loop having a downward lead 47 and an upward lead 48, the latter being utilized to impart the desired upward motion to the carriers. Herein the two loops cross each other adjacent the juncture of the main and branch incoming tracks, and at this point I have provided two grooved guide wheels or sheaves 49 and 50, which serve to guide the two leads of the loop. The lower portion of the loop is herein guided by a grooved guide wheel or sheave 51. The latter is herein rotatably mounted in a spindle 52, inclosed within a casing 54, which latter will in practice be placed adjacent the counter. The sheave wheels 49 and 50 are herein rotatably mounted on a spindle 55, which may be supported on a suitable bracket 56, the latter in the present instance being utilized as a part of the supporting means for the branch incoming or receiving track 29.

When the carrier is introduced upon the rails of the branch incoming or sending track 41 at the openings or offset portions 42, its cable gripping device should be caused to grip the cable so as to drive the carrier. For this purpose, I preferably provide a gripper actuating cam 57 (see Figs. 1, 5 and 6), which is adapted to engage the cable gripping arm 23 and throw the same from the position shown in Fig. 1 into operative engagement with the cable. The power for forcing the carrier against the cam as just described is herein furnished by the hand of the operator. When the carrier is thus engaged by the cable, it is driven upwardly along the vertical portion of the branch incoming or sending track 41, and is carried onto the main incoming track 16, from whence it will pass to the cashier's station (not shown). As a means for preventing any possibility of the carrier escaping laterally at the juncture of the main and branch tracks, I have herein provided a guard-plate 58, placed in a vertical plane at one side of the main incoming track (see Figs. 1, 2, 3, 4 and 5).

It will be remembered that a carrier in traveling from a given drop station to the cashier's station passes by any intervening drop stations, without descending into such stations. This feature has several notable advantages, among them being the fact that the carrier is required to travel a much less distance than in systems of the type in which the incoming carrier is obliged to descend into each and all of the intervening drop stations on its way to the cashier's station. Another advantage is that the carrier cannot be stopped and tampered with at the intervening stations. Still another advan-

tage is the elimination of the noise as well as the wear and tear upon the parts, caused by the carriers traveling through all the branch stations. It will be evident that, 5 owing to the provision of the loop already described in connection with the station, a carrier passing such station along the main incoming track must be disengaged from and reengaged with the driving cable at 10 opposite sides, respectively, of the looped portion. To this end, the incoming carrier on the main incoming track 16, as it nears the loop, is disengaged from the cable by a cam 59, which engages the pivoted cable gripper 23, thus opening the same and allowing the carrier to proceed under its momentum past the loop, when it may be reengaged with the cable by another cam 60, which engages the arm and restores it to 15 its gripping engagement with the cable. If desired, the speed of the carrier in approaching this cam may be increased by providing the main incoming track 16 with a depressed portion 61, commencing at a point 20 adjacent the releasing cam 59. The normal running position of the lower strand of the main incoming portion of the cable is as shown in Figs. 1 and 2, and in full lines in Fig. 3. When, however, the carrier which 25 has been previously engaged with the cable is traveling along the main incoming track, the cable is lifted from its normal position and drawn toward the right into the position indicated in dotted lines in Fig. 3, but when the carrier reaches the cam 59, and the latter disengages the gripper from 30 the cable, the latter will snap downwardly toward the left (Fig. 3) to a position where it will be out of the way of a carrier rising from the branch incoming or sending track 40 onto the main incoming track 16. When 35 the carrier reaches the cam 60, the relation of the cable to the track and the cam is such that the latter will reengage the gripper with the cable, and the latter in traveling 40 toward the left (Fig. 1) will be lifted to a point midway the rails of the main incoming track. Subsequently, after the passage 45 of the carrier, the cable will again descend to its normal level, as shown in Fig. 1.

The general operation of the specific embodiment of my invention hereinbefore described is as follows:

The carrier containing the money and 55 sales slip is introduced onto the branch incoming or sending track 41, where it is engaged with the cable and is driven along the branch incoming track into coöperation with the main incoming track, along which 60 it passes to the cashier's station (not shown), at some distant point, as is customary; but after the change is made, and the carrier is placed in coöperation with the main outgoing track, the carrier travels along the

latter track, and is diverted therefrom at 65 its proper station by the diverting tracks into coöperation with the branch outgoing or receiving track, from whence it may be removed in the manner hereinbefore described. 70

While I have herein shown and described one specific form or embodiment of my invention for illustrative purposes, and have disclosed and discussed in detail the construction and arrangement incidental to one 75 specific application thereof, it is to be understood that the invention is limited neither to the mere details or relative arrangement of parts, nor to its specific embodiment herein shown, but that extensive deviations from 80 the illustrated form or embodiment of the invention may be made, without departing from the principles thereof.

Having thus described my invention what I claim and desire by Letters Patent 85 to procure is:

1. A store service apparatus comprising, in combination, a branch track; a main track having an interruption at its juncture with said branch track; a carrier having main 90 guides for coöperation with said tracks and a supplemental guide; means for propelling said carrier along said main track past said juncture; and means to coöperate with said supplemental guide to support the carrier 95 in its travel across said interruption.

2. An overhead carrier system comprising, in combination, a main line track having a pair of rails one of which has a gap in its length, a branch track opening laterally to 100 the main track having a pair of rails terminating at the ends of the gap and guards independent of said tracks disposed at each side thereof at the gap and between which the carrier passes. 105

3. An overhead carrier system comprising, in combination, a main line track having a pair of rails one of which has a gap in its length, a branch track opening laterally to the main track having a pair of rails terminating at the ends of the gap and guards independent of said tracks disposed at each side thereof at the gap and between which the carrier passes, one such guard adapted to underride a portion of a throughbound 110 carrier and support it at the gap and constructed to permit the passage of a carrier along the branch and part of the main track. 115

4. An overhead carrier system comprising, in combination, a main line track having a 120 pair of rails disposed in a substantially vertical plane to receive a carrier between them, the lower of which rails has a gap in its length, a branch track having a pair of upstanding rails terminating at the ends of the 125 gap and a fixed support laterally adjacent and paralleling said main track positioned to underride a portion of a throughbound

- carrier and support it at the gap and constructed to permit the passage of a carrier along the branch and part of the main track.
5. An overhead carrier system comprising, in combination, a main line track having a pair of rails disposed in a substantially vertical plane to receive a carrier between them, the lower of which rails has a gap in its length, a branch track having a pair of up-
10 standing rails terminating at the ends of the gap, a fixed support laterally adjacent and paralleling said main track positioned to underride a portion of a throughbound carrier and support it at the gap and con-
15 structed to permit the passage of a carrier along the branch and part of the main track and a guard on the opposite side of track adjacent said gap between which and said support a portion of the carrier passes.

6. An overhead carrier system comprising, 20 in combination, a main line track having a pair of rails disposed in a substantially vertical plane to receive a carrier between them, the lower of which rails has a gap in its length, a branch track having a pair of up-
25 standing rails terminating at the ends of the gap and guards adjacent the gap at opposite sides of the plane defined by said track to prevent carriers from leaving the tracks laterally thereof as they pass the gap. 30

In testimony whereof I have signed my name to this specification in the presence of two subscribing witnesses.
